FLUID DRIVE MECHANISM

Franklin W. Marshall, Pittsburgh, Pa.

Application May 21, 1954, Serial No. 431,415

7 Claims. (Cl. 60—52)

This invention relates to a fluid drive mechanism. More particularly the invention relates to a hydraulic operating mechanism as applied to a hospital bed which has adjustable head, knee and foot panels which are movable up and down to adjust the panels to various positions to make a patient on the bed comfortable.

Nursing attendants are not always available to make adjustments of a hospital bed. It is desirable that a patient may be able to easily make the desired adjustments of the bed panels while the patient is on the bed.

Experience has shown that the bed panels should be positively raised and lowered and that the motion should be slow and smooth to aid the patient in finding a comfortable position. It is important also that the raising and lowering movement should be limited and when a desirable adjusted position of the panels is found, that the panels shall remain fixed in that position until a changed position is desired.

For patients who have heart trouble or trouble with the blood circulation, it has been found that such patients can obtain great relief by having the feet elevated while lying on his back. The natural tendency is for the knees to be raised as the feet are raised but the medical profession has found that it is very desirable to have independent as well as coordinated adjustment of the knee and foot panels to obtain the maximum benefit for a patient.

It is important to have a bed panel adjusting mechanism that is simple to operate with the minimum number of parts and to be dependable in its operation.

Another important feature for a hospital bed is to provide a panel adjusting mechanism which is quiet in its operation to avoid annoyance to the patient operating the panels and other patients in a hospital.

The primary object of the present invention is to provide a fluid drive mechanism for obtaining a positive reciprocating motion with control means for stopping and starting the motion and for positively holding the moving part in any desired adjusted position.

Another object of the invention is to provide a fluid operating mechanism for a hospital bed having adjustable head, knee and foot panels by which the panels may be independently adjusted and locked in adjusted position.

Another object of the invention is to provide an electrical control of a fluid operating mechanism for adjustable head, knee and foot panels of a bed by which all adjustments and the holding of the panels in a desired adjusted position may be carried out with a single control switch for each panel.

A further object of the invention is to provide a fluid drive adjusting mechanism for a bed having knee, and foot panels in which the two panels may have independent up and down adjustments as well as coordinated adjustments.

With these and other object and features in view, the invention consists in the controlled fluid operating mech-

2

anism herein illustrated and described and particularly defined in the appended claims.

The various features of the invention are illustrated in the accompanying drawings in which:

Fig. 1 is a plan view with parts omitted of the adjustable panels of a hospital bed having the improved fluid operating mechanism applied thereto;

Fig. 2 is a view in side elevation of the bed panels and the fluid operating mechanism shown in Fig. 1;

Fig. 3 is a detail view in elevation of the limiting switch mechanism for coordinating the operation of foot and knee panels;

Fig. 4 is a double throw electric switch by which operation of the head panels may be controlled;

Fig. 5 is a diagrammatic view of the fluid operating mechanism showing the cylinders for operating each of the bed panels, the piping connections between the pump and the cylinders and the valves in the piping connections for controlling the operation of the cylinders;

Fig. 6 is a wiring diagram showing the electrical arrangement for operating the fluid pump and the valve operating solenoids; and

Figs. 7 and 8 are diagrammatic views of a four way valve to be used alternatively for the four valves for each of the cylinders as shown in Fig. 5.

The fluid operating mechanism of the present invention has many applications where a reciprocating motion is desired with controls for stopping and holding a moved part in any desired position. The application of the fluid operating mechanism to the head, knee, and foot adjusting panels of a hospital bed is shown in Figs. 1 and 2. These drawings show only the deck portion of the bed. This deck portion is made up of a head panel 10 which is pivotally connected with a fixed panel 11 by pivots 12. A knee panel 13 is pivoted at the rear side to the fixed panel 11 by pivots 14 and at the front end to the foot panel 15 by pivots 16. These panels are covered by a woven wire spring, the character of which is shown at 17 in Fig. 1. This spring continues from the front end of the head section to the back end of the foot section as a continuous sheet and is connected to the panels by springs 18. The panels are pivotally movable with reference to one another and the spring sheet is generally covered by a sponge rubber mattress which contains a large number of cavities on one side which permits the mattress to bend and flex with the spring sheet when the sections are adjusted at different angles in order to assume a position on the bed deck which is comfortable for a patient on the bed.

The head panel is moved about the pivots 12 by means of a hydraulic piston which is operated in a cylinder 19. The cylinder is pivotally connected at 20 to a frame member 21 (Fig. 1). A piston rod connected to the piston in cylinder 19 is pivotally connected to an arm 23 fixed on a shaft 24 which is journaled between frame members 25 at opposite sides of the bed. Another pair of arms 26 which are fixed on opposite ends of the shaft 24 are connected by links 27 with the head panel by pivots 28. When the piston in the cylinder 19 is

reciprocated the head panel is moved up and down to the positions illustrated in solid and dash lines (Fig. 2). The arms 26 and links 27 support the head panel in a horizontal position when the piston is moved to a down position to place the spring sheet in a substantially horizontal position.

The fixed section 11 is attached to the side rails 25 of the bed as shown in Fig. 2 and supports the rear end of the head panel and the front end of the knee panel at the normal horizontal level of the spring sheet.

The knee panel is moved up and down by means of a piston in a cylinder 29 which is pivotally connected to the frame member 21 by a pivotal connection 30 (Fig. 2).

A rod 31 connected to the piston in cylinder 29 is connected with an arm 32 which is fixed upon and rotates with a shaft 33 (Figs. 1 and 2) which is journaled between the bed frame side members 25. Arms 35 fixed on opposite ends of the shaft 33 are pivotally connected with links 36 that are pivotally connected at their upper ends to the rear end of the knee section. When the piston in the cylinder 29 is reciprocated the shaft 33 is rotated and through arms 35 and links 36 the knee section is raised and lowered.

The foot panel 15 has no direct connection with the power drive mechanism but is moved up and down by means of a cradle 37 which is pivotally connected at 38 (Fig. 2) to downwardly extending frame members 39 secured to the bed frame members 25.

Cradle 37 is composed of normally horizontal guide arms 40 which are connected together by rod 41. To the horizontal arms are connected inclined cam arms 42 which extend down to a level below the bed frame and are connected to pivotal arms 43 which have the pivotal connection 38 with the bed frame. Bracing rods 44 are connected between the guide arms 40 and pivotal arms 43 to make the cradle a rigid unit structure. The cradle is given an oscillating movement, for the purpose of raising and lowering the foot panel, by means of a piston in a cylinder 45. The front end of the cylinder 45 is connected by means of supporting rods 46 with the rear of the bed frame. The piston rod 47 is adjustably connected with an axle 48 which is mounted on rails 49 by means of trolleys or rollers 50 at each end of the axle. The rails 49 are secured to the bed frame. The axle 48 also has rollers 51 which ride under the cam rods 42 of the cradle, and as the axle is moved toward the head of the bed by reciprocation of the piston in the cylinder 45, the cradle is oscillated to raise the foot panel. When the foot panel is raised, rollers 52 (Fig. 2) on the rear end of the foot panel ride along the horizontal bars 40 of the cradle.

The details of the operation of the hydraulically operated cylinders 19, 29, and 45 are illustrated diagrammatically in Fig. 5. These diagrammatic cylinders are given the same numeral as that shown in Fig. 1. This diagram illustrates the piston in the cylinder 19 and the valves for that cylinder position ready to receive a pressure fluid at the front ends of the cylinder for raising the head panel of the bed deck. The valves for cylinders 29 and 45, of Fig. 5 are in a neutral position to which they are moved by springs 94 of operating solenoids when the electrical current is cut off from the solenoids. Each cylinder is a double-acting cylinder in that piping connections 53 and 53' are connected at opposite ends of the cylinder by which fluid under pressure may be introduced for the purpose of driving the piston in opposite directions. The pressure fluid is delivered from a pump 54 operated by an electrically-driven motor 55. The fluid under pressure flows through a supply line 56 past a check valve 57, thence through a control valve 58 to the cylinder. Each of the cylinders 19, 29, and 45 have the similar piping connections 53 and 53', and similar sets of check valves 57 and control valves for each end of the cylinder. The line 56 is extended to deliver fluid under pressure to each end of each cylinder. With this arrangement the check valves 57 prevent the return flow of liquid in the pressure supply line, and hold the pistons in fixed position when the valve operating solenoids in the cylinders are disconnected from electrical current. Preferably compression springs of a predetermined compression strength are located at each end of the cylinders 19, 29, and 45 to limit the reciprocating motion of the piston within the cylinder. When the piston moves into contact with the springs at the ends of the cylinder, the fluid pressure developed by the pump 54 is maintained substantially uniform by means of a relief valve 59 operated by a spring 60 to permit fluid to pass through a line 61 and line 62 to a return line 63 and thence to a sump

64. When fluid is introduced to the front ends 65 of the cylinders to move the pistons, fluid is returned from the rear end of the cylinders through a line 53', thence through a valve 58' to a line 66 connected with all of the valves 5 which in turn are connected with the cylinders. When the pressure fluid is introduced into the front end 65 of the cylinders, the panels of the bed deck are raised and will be held in the raised position by the check valves 57 so long as the patient in the bed desires to have them in raised position. When it is desired to change the position of the panels of the bed deck, an electrical switching apparatus as hereinafter described is operated to shift the position of the valve channels to introduce pressure fluid into the rear end of the cylinders and exhaust fluid from the front end of the cylinders through the valve. When the valves are shifted, the fluid under pressure will be introduced into the rear end of the cylinders and the pistons will be positively driven to lower the bed panels under a controlled operation of the cylinders. 15 Since each of the fluid supply lines has a check valve, the bed panels will be locked in any adjusted position while rising or while being lowered, and if the motor continues to supply fluid to the supply line when the pistons reach the end of the reciprocating movement, the relief valve 20 59 will permit the fluid delivered by the pump to return to the sump 64. In order to avoid any stoppage of the valves or pistons, the oil or pressure fluid drawn from the sump 64 by the pump 54 is passed through a filter 68. At the time a switch is operated to stop the operation 25 of a panel, the valves 58 and 58' of the cylinder being controlled will be shifted to a neutral position by springs 94 to cut off the return of fluid from the hydraulic cylinder to the sump 64.

In the normal operation of the bed panels, the up and 30 down movement of the panels by means of the hydraulic cylinders is not limited, except at the time that the pistons reach the end of their strokes in the cylinders as explained above. It has been found, however, that it is important to coordinate the movement of the foot and 35 knee panels in order to avoid placing the panels in a position which is not desirable for the comfort of a patient. Accordingly a limiting control mechanism is used in connection with the operation of the foot lifting cradle for controlling the upward movement of the foot panel and the downward movement of the knee panel. As shown in Figs. 1 and 3, a cam arm 69 is mounted 40 on the axle 48 and projects rearwardly toward the rear end of the foot panel. A cam 70 is fixed on the shaft 33 for operating the knee panel and bears against a lever 71 which is pivotally connected to the guide frame 49 by a pivot 72. The front end of the lever 71 carries 45 electrical switches 73 and 74 which control the electrical circuits for operating the cylinders 29 and 45. The switches 73 and 74 have rollers 75 which bear against an inclined cam face 76 on the cam 69, and during the 50 normal operation of the foot and knee panels, the cams 70 and 76 are so shaped that the rollers 75 do not bear against the cam face 76 to keep the electrical circuit closed. As shown in the drawings, the electrical circuits controlled by the switches 73 and 74 will be closed so long as the surface of the panels 13 and 15 make a straight angle, but if the knee panel were to be depressed below the level of the surface of the foot panel, 55 then the guide roll of the switch 73 will contact the cam surface 76 as illustrated in full lines in Fig. 3, and at such time the electrical circuit for operating the knee section will be broken to limit the angular position between the surface of the knee panel and the surface of the foot panel to a predetermined angle. Since the 60 switches 73 and 74 control the operation of the foot and knee panels, both panels will be cut out of operation until the angular position between the panels is adjusted. The condition discussed above can only occur during 65 the downward movement of the knee section, and if the

limiting switches 73 and 74 are operated to break the circuits, then it will be necessary to raise the knee panel to adjust the angular position before either of the panels may be adjusted further in a downward course.

The wiring diagram for operating the pump motor and the switches for controlling the flow of liquid through the hydraulic cylinders is illustrated by the conventional wiring diagram (Fig. 6). Switches 77 are used for controlling the upward movement of the panels, and switches 78 are used for controlling the movement of the panels downwardly. When any of the switches 77 are put into operation, arms 79 are brought into contact with points 80 which connect a line 81 to one terminal of a power circuit 82. The closing of the switch also brings current from the power circuit 82 through the line 83 and a relay 84 back to the line 85. The relay thereupon closes the circuit 86 of the motor 55 to start the motor, and at the same time current flows through solenoid 87 for operating valve 58' for directing pressure fluid at the rear end of a cylinder back to the sump. The valve 58 will be at this time in position to supply pressure fluid to the front end of the cylinder because the valve 58 was placed in this position by a spring 94 when the electrical current was cut off of the operating solenoid. Three cylinders are illustrated in the drawing, and three separate switches are used, one switch for each cylinder. The electrical control of the pump and valves for each cylinder is the same. The operation of the down operating switches 78 is connected through the circuit so that when the switch is moved to contact the points 88, at the bottom of the diagram, the lines 81, 83 are closed to first start the motor 55 before solenoid switch 89 is operated to shift the valve 58 to exhaust fluid from the front end of the cylinder to the sump. The valve 58' of this cylinder, while in neutral position, made a connection to supply pressure fluid to the rear end of the cylinder.

Preferably the switches used for operating the circuits are three position switches such as illustrated in Fig. 4. In normal position the switch arm 90 stands in a vertical position, being held in this position by spring arms 79 that form one side of an electrical circuit. When the switch arm 90 is moved to the right, a contact point 80 will be connected with an arm 79 to close an electrical circuit 81-83 for operating the pump and the circuit for operating one of the solenoids 87 to shift valve 58'. When the arm 90 is moved to the left, an arm 79 will be moved to the position to make a contact with a circuit contact 88 to close the motor circuit and the circuit to operate solenoids 89 to shift valve 58. In the assembled form of the switches of Fig. 4, the switch members 77 and 78 will be mounted side by side so that a movement of switch arm 90 to the right will close two circuit contacts 80 for an up movement of the panels. When arm 90 is moved to the left, two contacts 88 will be made for downward movement of a panel.

In Figs. 1 and 2 is illustrated the arrangement of a switch box 93 with three switches therein so that arms 90 extend out of the box. The switch box is pivotally mounted on a side rail 25 of the bed so that it may be moved up into position to be readily available for operation by a patient with the patient lying on the bed. The switch arms 90 may be moved to "up" or "down" adjusting positions in order to set the panels in any desired angular position for obtaining a comfortable position of the patient on the panels. When the switch arms are released, the switch will move to a neutral position, and the movement of the panel will cease.

The valves 58 and 58' illustrated in Fig. 5 are four-way valves which are operated by solenoids such as solenoids 87 and 89 illustrated in Fig. 6. When the switch arm 90 sets valves 58', for example, to exhaust pressure fluid from the back end of a cylinder to the sump for an "up" movement, the valve 58 had been previously set to supply pressure fluid to the front end of the cylinder. Vice

versa when the switch arm 90 is operated to set valve 58 to exhaust pressure fluid from the front end of the cylinder, the valve 58' had been previously set to supply pressure fluid to the rear end of the cylinder. At any time that the switch arm 90 is released, it is moved to a neutral position by spring arms 79, the electrical circuit is opened and springs 94 move the valves 58-58' into a position to connect both ends of the cylinder to the lines 53 and 53' which are closed by the check valves 57.

In Figs. 7 and 8 are illustrated two positions of a four-way valve which may be used for the two valves 58 and 58' that are used with the fluid operated cylinders illustrated in Fig. 5. The valve of Figs. 7 and 8 is illustrated as a rotary mounted plug type valve having four channels therein for conducting fluid to and from the piston operated cylinder. Solenoids 95 and 95' are mounted at opposite ends of the valve for the purpose of rotating the valve through an arc of approximately 45°. The solenoid 95 may be mounted in the circuit illustrated in Fig. 6 to take the place of solenoid 87 and would be operated only when switch 77 is closed. The solenoid 95' would then be connected with switch 78 to be operated only when switch 78 is closed. In one position of the valve (Fig. 7) as set by the solenoid 95, diametrically arranged channels 96 will introduce pressure fluid from pump 54 to the front end of a cylinder while exhausting fluid from the other end of the cylinder to a sump 64. When the current is cut off, springs 97 and 98 engaging the solenoids will move the valve member into a position to close all ports into and out of the valve. When solenoid 95' is operated the valve plug will be rotated about 45° in a direction opposite to the rotation made by solenoid 95 to set the valve as shown in Fig. 8 to deliver pressure fluid from pump 54 through diagonal channel 99 to the rear end of the cylinder while exhausting fluid from the front end of the cylinder through diagonal channel 100 to the sump 64. With this arrangement therefore the four-way valve which would be connected in the supply line and the return line will serve the functions of the four-way valves 58 and 58' and the two check valves 57.

The normal operation of the bed panels may be carried on by a patient who is convalescing. If it is desired that the panels should not be adjusted by the patient, then a switch in the main electrical circuit 82 may be opened and controlled only by a nurse, and thereby leave the adjustment of the bed panels to a nurse. The desirable feature of the present invention, however, is to supply the electrical power to the switch box 93 so that the patient may be able to adjust the panels of the bed without calling upon a nurse.

From the construction described above, it will be apparent that each of the panels may be operated independently of the other. The panels may be moved up and down simultaneously. Further, one panel may move up while other panels are moved down. A limiting control is used with reference to the downward movement of the knee panel in order to prevent the knee and foot panels from being placed into an angle which is uncomfortable and should not logically be used.

It will be apparent furthermore that the fluid drive mechanism which is illustrated and described herein has a wide variety of uses in that it can positively move a desired member through a reciprocating movement and hold the moving member into any desired position by the mere operation of a single control switch.

As shown in Fig. 6 the arrangement of the switches 77 and 78 is to close the motor operating circuit in advance of closing the solenoid valve operating circuit. These switches may be directly connected with the power circuit to simultaneously close both a motor operating circuit and a valve operating circuit so that the relay and its motor circuit closing switch would not be required.

The preferred form of the invention having been thus described, what is claimed as new is:

1. A fluid drive mechanism comprising a cylinder with

a piston mounted to reciprocate therein, a fluid supply line at each end of the cylinder, a check valve in each of the fluid supply lines, a sump, an electrical motor-driven pump connected with the sump to introduce fluid under pressure to the supply lines, a fluid return line extending from each end of the cylinder to the sump, a four-way solenoid operated valve in each line between the check valve and the cylinder, said four-way valve having a channel for connecting the supply line with the cylinder and a channel for connecting the cylinder with a return line leading to the sump, an electrical circuit for the solenoid valve arranged to position the valve to supply pressure fluid to one end of the cylinder while exhausting fluid from the other end of the cylinder, said electrical circuit being connected with the pump motor by a relay in series therewith to drive the motor and operate a solenoid valve, and a switch in said circuit for selectively operating the solenoid control valve to control the direction of movement of the piston.

2. The fluid drive mechanism defined in claim 1 in which the electrical circuit starts the motor in advance of the closing of the relay circuit for operating the control valves.

3. A fluid drive mechanism comprising a cylinder with a piston mounted to reciprocate therein, a fluid supply line at each end of the cylinder, a check valve in each of the fluid supply lines constructed to permit liquid flow in the direction of supply to a cylinder only, a sump, an electrically driven motor pump connected with the sump to introduce fluid under pressure to the supply lines, a fluid return line extending from each end of the cylinder to the sump, a four-way solenoid operated valve having a separate port for registration with a line connected to each end of the cylinder, diametrically arranged delivery ports in the valve arranged to communicate with the first-mentioned ports with one delivery port being connected with a pressure fluid line when the other delivery port is connected with the sump, a valve body in the valve having channels to connect the cylinder and delivery ports whereby fluid under pressure may be directed against either side of the cylinder piston while fluid is being conducted away from the end of the cylinder opposite the end where pressure fluid is introduced, electrical circuits for operating the valve solenoids to selectively set the valve channels to control the movement of the cylinder piston, and means to adjust the valve body to connect the lines at each end of the cylinder with the fluid supply lines when the electrical current to the valve solenoids is cut off.

4. The fluid drive mechanism defined in claim 3, in which a three-position switch is used in the electrical con-

nections to the valve solenoids, said switch being connected with springs arranged to normally set the switch in neutral position to open the solenoid circuit and said switch being manually moveable to two positions to supply electrical current to operate the valve solenoids to selectively set the valve to deliver pressure fluid to each of the ends of the cylinder while simultaneously discharging fluid from the opposite end of the cylinder, and springs engaging the valve body to position the body when the switch is in neutral position to connect both ends of the cylinder with the fluid supply lines to lock the piston in fixed position in the cylinder.

10 5. The fluid drive mechanism defined in claim 1 in which a three-position control switch for the motor and flow valves is normally held in a neutral position by springs to cut off the electrical power to the motor and valve solenoids and said switch being manually movable to two positions to set the valves to selectively deliver pressure fluid to opposite ends of the cylinder.

15 6. The fluid drive mechanism defined in claim 1 in which the switch is a three-position switch arranged in one position to operate, a solenoid valve to move the cylinder piston in one direction and in another position to operate a solenoid valve to move the cylinder piston in the opposite direction and in a third neutral position to disconnect the electrical circuit from the solenoid valves, and springs connected with the solenoid valves are arranged to set the valves to connect each end of the cylinder with the fluid supply line when the neutral position of the switch disconnects the electrical current from the solenoids whereby the operating fluid is locked in position at each end of the cylinder by the check valves in the supply lines.

20 7. The fluid drive mechanism defined in claim 6 in which the switch is arranged for manual operation to separately secure a reciprocation movement of the cylinder piston in one direction or the other while being held in a circuit closing position by an operator and a spring mechanism connected with the switch to move it into the neutral position when it is manually released.
